UNITED STATES PATENT OFFICE.

FRANK AIKEN, OF ELKINS PARK, PENNSYLVANIA, ASSIGNOR TO ARTHUR ATWATER KENT, OF ARDMORE, PENNSYLVANIA, DOING BUSINESS AS ATWATER KENT MANUFACTURING WORKS, OF PHILADELPHIA, PENNSYLVANIA.

ELECTRIC IGNITION APPARATUS.

1,375,884.

Specification of Letters Patent. Patented Apr. 26, 1921.

Application filed June 20, 1919. Serial No. 305,664.

To all whom it may concern:

Be it known that I, FRANK AIKEN, a citizen of the United States, residing in Elkins Park, county of Montgomery, and State of Pennsylvania, have invented certain new and useful Improvements in Electric Ignition Apparatus, of which the following is a specification.

My invention relates to electric ignition apparatus, particularly such as is employed for igniting or firing combustible mixtures in internal combustion engines.

It is the object of my invention to provide ignition apparatus which shall be effective in igniting explosive mixtures under adverse circumstances, such as starting in cold weather, under conditions of low battery voltage, or under conditions widely differing as to voltage of battery or any other source of current.

To these ends I have devised vibrating jump spark apparatus having the desirable characteristics of satisfactory operation over wide ranges of voltage of the source of current, maintaining substantially the same frequency of vibration throughout a wide range of voltage variation, and involving but small variation of primary current strength.

My invention resides in apparatus having the characteristics referred to and of the nature and structure hereinafter described and claimed.

For an illustration of one of the various forms my invention may take, reference is to be had to the accompanying drawing, in which:

Figure 1 is a diagrammatic view of ignition apparatus embodying my invention.

Fig. 2 is a sectional view, some parts in elevation, of a vibrator unit embodying my invention.

Referring to the drawing, P is the primary coil or winding of a jump spark induction coil one terminal of whose high tension secondary S is connected to ground or frame F of the engine or motor car, and whose other terminal is connected to the rotary distributor D co-operating in well known manner with the distributor segments or contacts and connected, respectively, to the spark plugs p of the different cylinders of the internal combustion motor.

In addition to the coil P there are in the

primary circuit of the induction coil the source of current or storage battery B, switch s, resistance R, and timer or interrupter contacts b and c, the latter connected to the ground or frame F, as is also one terminal of the battery B, it being understood, however, that my invention is not limited to a system involving grounding as herein described. The interrupter contact b is actuated by the cam d driven in definite relation with the crank shaft of the engine or motor, and generally at half the speed of the engine shaft, the aforementioned distributor D rotating at the same speed with the cam d, as well understood in the art. In shunt to the interrupter b, c, is connected as usual a condenser K.

In a branch circuit is connected the vibrator mechanism comprising the spring contact e, adapted to be pushed by the button f into engagement with the contact g connected to one terminal of the magnet coil M, whose other terminal connects to the vibrator V carrying the interrupter contact h co-acting with the interrupter contact i carried by the thin or weak leaf spring j tending to flex in such direction as to cause the contact i to follow the contact h, the extent of movement of the contact i, however, being limited by the head k of a screw or rivet extending freely through an aperture in the spring j and carried by the post m. The spring j is connected to the frame or ground F. In shunt to the interrupter contacts h and i is connected the condenser K.

The magnet coil M surrounds a tube or shell o of brass or other well conducting material carried by a cylindrical or other core piece q, of iron or other suitable magnetizable material, carried by the iron yoke r having the horizontally extending portion r¹, Fig. 2, secured by screws t to any suitable support, as u. The screws t may engage in the closing cap u¹ to hold the same against the base member u. Between the cap u¹ and the base member u is formed a cavity in which are located the aforesaid spring contacts e and g, the push button f extending through the cap u¹ for actuation on the contact e, the push button carrying a transversely extending pin f¹ which engages in suitable slots or depressions to lock the push button f, and therefore the spring

e in either the circuit closing or circuit opening position.

The vibrator member *V* is preferably of iron or other suitable magnetizable material and has its lower end disposed opposite the free end of the member *r*¹ and is supported thereon by the short easily flexed leaf spring *v*, which in effect constitutes the pivot of the vibrator *V*, the spring *v* being secured to both the under side of the member *r*¹ and to the lower end of the vibrator *V*, as indicated in Fig. 2. A magnetizable armature or solenoid core member *w* is secured at its one end to the vibrator *V* and has at its other end the head or enlargement *w*¹ of magnetizable material presented to the end of the magnetizable core member *g*, in the end of which may be disposed a button *g*¹ of non-magnetizable material to prevent the head *w*¹ from contacting with the end of the core *g*, which due to remanent magnetism might hold the vibrator *V* in the open circuit position. The interrupter contact *i* may be adjusted as to its position by the screw *w*, whose adjustment will flex the upper end of the post or standard *m*.

While in Fig. 2 I have shown my vibrator structure assembled as a unit, it will be understood that my invention is not limited thereto, since the parts may be assembled, disposed or mounted in any suitable way.

The operation is as follows:

Assuming the motor at rest and that it is desired to start the same, as in extremely cold weather when the source *B*, when a storage battery, may have an effective voltage which is approximately only one-third of its normal voltage at ordinary temperatures, the operator closes the switch *s* and pushes the button *f*, bringing the contact *e* into engagement with contact *g*, thereby closing the branch circuit through the vibrator mechanism. The engine is then turned over or cranked by hand or by the usual electric motor energized from any suitable battery, as for example, the aforesaid battery *B*. The cam *d* and distributor *D* rotate in unison, and the interrupter contact *b* periodically engages and separates from its companion *c*. With the spark control lever retarded to such position that the contact *b* separates from contact *c* at a position of the piston of the cylinder next to be fired beyond dead center in the outward or power stroke, the magnet *M* is energized, attracting the core structure *w*, *w*¹ of small weight or inertia toward the left, Fig. 1, breaking circuit at the contacts *h* and *i*, de-energizing the magnet, causing reestablishment of the circuit, followed by a second break, and so on. The current in the primary *P* is accordingly established and broken rapidly a number of times in succession, each circuit rupture producing a spark at the spark plug of the cylinder referred

to. With the contacts *b* and *c* in circuit closing position, the operation of the vibrator mechanism will not produce sparks at the plugs, or at any rate, will not produce sparks of sufficient energy to ignite the combustible mixture. But upon separation of the contact *b* from contact *c* all the current through the primary *P* is interrupted at *h*, *i*, with the production of effective sparks. The shower or succession of sparks positively ignites the mixture and the engine starts and continues to run, the operator thereafter releasing the push button *f* to cut the vibrating mechanism out of circuit, whereupon the single spark system, controlled by contacts *b* and *c*, continues to function in the usual and well known manner, a spark being produced at or upon each separation of the contact *b* from its companion *c*.

From the foregoing description it will be seen, therefore, that the vibrator mechanism is effective only when the single spark interrupter *b*, *c* is in open circuit position.

The vibrator mechanism of the character described is particularly suitable in that notwithstanding wide ranges in the effective voltage of the source *B*, or of any other source of current which may be employed, the frequency or rapidity of action of the vibrator remains substantially constant, whereby whether the source of current have low or high effective voltage, the frequency of operation will remain substantially the same, always producing a series of effective sparks and the average value of the current, as measured, for example, by a galvanometer or ammeter of D'Arsonval type, through the primary *P* and the vibrator mechanism remains substantially constant throughout a relatively wide variation in voltage of the source of current.

These desirable characteristics of operation are contributed to by the small weight or inertia of the moving system of the vibrator mechanism, and particularly of the movable core structure *w*, *w*¹, and by the tube or shell *o* of material of good conductivity in which currents are induced of such magnitudes as to produce magneto-motive-forces reacting with the magneto-motive-force produced by the magnet coil *M* as to maintain substantially constant the forces acting upon the core structure *w*, *w*¹ throughout wide variation in voltage of the source *B* and by reaction causing the average current above referred to to remain substantially constant notwithstanding relatively wide changes in voltage of the source, as *B*.

By way of example, it may be stated that where a storage battery, as *B*, of six cells, such as used commonly in 12 volt systems on automobiles, the effective voltage of such source may under very low temperature con-

ditions, such as sometimes obtain in winter in northern territory, be reduced to approximately four volts, which would often or generally be unsuitable for ignition purposes with the usual single spark system, such, for example, as involves contact mechanism like the above described contacts *b*, *c* controlled by cam *d*. Yet with the vibrator mechanism constructed and operating as described, a series or shower of sparks is given for each interruption of the contacts *b*, *c*, the frequency or rapidity of succession of the sparks, dependent upon the frequency of the vibrator *V*, remaining substantially constant.

By employing a magnet or solenoid structure as described, the end or head *w*¹ of the movable core structure is located substantially at the middle of the length of the solenoid or magnet winding where the magnetic field is a maximum. This is of importance particularly at the low voltages, this structure insuring at such low voltages sufficient magneto-motive-force and flux to cause the vibrator to act; yet with higher voltages due to the effect of the tube *o* the magnetic attractive forces do not materially increase, with the aforesaid result that the frequency of vibration remains substantially constant with a substantially constant primary current, with resultant substantially uniform flatness of spark or spark heat.

While it will be understood that the resistance *R* may be omitted, if used it serves to prevent too great a current flowing in the primary circuit in case the switch *s* is left closed and the contact *b* should remain, when the engine stops, in engagement with contact *c*. The resistance *R* may be of any suitable material, either of a metal having high positive temperature coefficient or one having zero or substantially no temperature coefficient, as may be desired. However, the magnitude of resistance *R* is never made so great that at highest engine speeds the magnitude of the primary current will be insufficient for producing effective or sufficiently hot sparks.

As an example of structure embodied in my invention, which, however, is not limited thereto, a vibratory mechanism which will operate satisfactorily throughout a range of voltage from 4 to 18 volts, and preferably employed in a 12 volt ignition system, may comprise a magnet winding *M* of 36 turns of No. 21 Brown & Sharpe gage copper wire, associated with a sleeve *c* of brass, approximately 60% copper, having a length of about nine-sixteenths of an inch, internal diameter five-sixteenths of an inch, and thickness .036 inch. Such structure, in combination with an induction coil primary *P* of approximately 416 turns, resistance approximately 2.24 ohms, associated with an iron core struc-

ture about five inches long and $\frac{3}{2}$ inch diameter, satisfactorily interrupts the primary current at approximately 126 times per second, with a frequency variation in this respect of about ten per cent. above and below the aforesaid normal frequency throughout the aforementioned voltage range. With the timer contacts *b*, *c*, open, and the cam *d* stationary, the average current in the vibrator mechanism is .24 ampere varying above and below that value about .02 ampere throughout the aforesaid voltage range.

What I claim is:

1. Ignition apparatus comprising the combination with an induction coil, of a source of current, vibrator mechanism interrupting the primary circuit of said induction coil at substantially constant frequency throughout a wide range of variation of effective voltage of said source of current, said mechanism comprising a magnet winding in series with the primary winding of said induction coil, a stationary core member, a movable core member, an interrupter contact moved by said movable core member, and a closed circuit tube associated with said winding.

2. Ignition apparatus comprising the combination with an induction coil, of a source of current, and vibrator mechanism interrupting the primary circuit of said induction coil and maintaining the average value of the primary current substantially constant throughout a wide range of variation of effective voltage of said source of current, said mechanism comprising a magnet winding, a stationary core member, a movable core member, an interrupter contact moved by said second core member, and a closed circuit of high conductivity associated with said magnet winding.

3. Ignition apparatus comprising the combination with an induction coil, of a source of current, and vibrator mechanism interrupting the primary circuit of said induction coil at substantially constant frequency and maintaining the average primary current substantially constant throughout a wide range in the effective voltage of said source of current, said mechanism comprising a magnet winding, a stationary core member, a movable core member, an interrupter contact moved by said movable core member, and a closed circuit tube of non-magnetic material of good conductivity associated with said winding.

4. Ignition apparatus comprising the combination with a source of current, of an induction coil, and vibrator mechanism for interrupting the primary circuit of said induction coil comprising a magnet winding, a stationary core member therefor terminating within said winding, a movable core member terminating adjacent said first

named core member within said winding, and an interrupter contact moved by said second named core structure.

5. Ignition apparatus comprising the combination with a source of current, of an induction coil, and vibrator mechanism for interrupting the primary circuit of said induction coil comprising a magnet winding, a stationary core member therefor terminating within said winding, a movable core member terminating adjacent said first named core member within said winding, and an interrupter contact moved by said second named core member, the movable system of the vibrator mechanism including said second named core member having small inertia.

6. Ignition apparatus comprising the combination with a source of current, of an induction coil, and vibrator mechanism for interrupting the primary circuit of said induction coil comprising a magnet winding, a stationary core member therefor terminating within said winding, a movable core member terminating adjacent said first named core member within said winding, an interrupter contact moved by said second named core member, and a closed circuit tube associated with said magnet winding and said core structures.

7. Ignition apparatus comprising the combination with a source of current, of an induction coil, and vibrator mechanism for interrupting the primary circuit of said induction coil comprising a magnet winding, a stationary core member therefor terminating within said winding, a movable core member terminating adjacent said first named core member within said winding, an interrupter contact moved by said second named core member, and a closed circuit tube of non-magnetic material of good conductivity associated with said core members and said magnet winding.

45. 8. Ignition apparatus comprising the combination with a source of current, of an induction coil, and vibrator mechanism for interrupting the primary circuit of said induction coil comprising a magnet winding, a stationary core member therefor terminating within said winding, a movable core member terminating adjacent said first named core member within said winding, an interrupter contact moved by said second named core member, and a closed circuit tube of non-magnetic material of good conductivity intervening between said magnet winding and said core members.

60. 9. Ignition apparatus comprising the combination with a source of current, of an induction coil, and vibrator mechanism for interrupting the primary circuit of said induction coil comprising a closed circuit tube of non-magnetic material of good conductivity, a magnet winding surrounding the same, sta-

tionary and movable core members terminating and spaced from each other within said tube intermediate the ends thereof, and an interrupter contact actuated by said movable core member.

70

10. Ignition apparatus comprising the combination with a source of current, of an induction coil, and vibrator mechanism for interrupting the primary circuit of said induction coil comprising a closed circuit tube of non-magnetic material of good conductivity, a magnet winding surrounding the same, stationary and movable core members terminating and spaced from each other within said tube intermediate the ends thereof, a vibrator supporting said movable core member and constituting therewith a moving system having small inertia, and an interrupter contact actuated by said movable core member.

80

11. Ignition apparatus comprising the combination with a source of current, of an induction coil, and vibrator mechanism for interrupting the primary circuit of said induction coil at substantially constant frequency throughout wide variations in the effective voltage of said source of current comprising a closed circuit tube of non-magnetic material of good conductivity, a magnet winding disposed upon said tube, a stationary core member projecting into said tube and terminating intermediate the ends thereof, a movable core member comprising a slender stem and a head thereon within said tube adjacent the end of said stationary core member, a vibrator carrying said movable core member and forming therewith a movable system having small inertia, and an interrupter contact actuated by said vibrator.

90

12. Ignition apparatus comprising the combination with a source of current, of an induction coil, and vibrator mechanism for interrupting the primary circuit of said induction coil comprising a magnet winding, a stationary core member therefor terminating within said winding, a movable core member terminating adjacent said first named core member within said winding, magnetizable material connected with said core members and completing the magnetic circuit external to said winding, an interrupter contact moved by said movable core member, and a closed circuit tube associated with said magnet winding and said core members.

100

13. Ignition apparatus comprising the combination with a source of current, of an induction coil, and vibrator mechanism for interrupting the primary circuit of said induction coil comprising a magnet winding, 125 stationary and movable core members terminating and spaced from each other within said winding, a magnetic yoke structure connected to one of said core members and partially completing the magnetic circuit ex- 130

ternal to said winding, a magnetizable vibratory member carrying the other of said core members and with said yoke structure completing the magnetic circuit of said winding, an interrupter contact actuated by said vibratory member, and a closed circuit of high conductivity associated with said core members and said magnet winding.

14. Ignition apparatus comprising the combination with a source of current, of an induction coil, and vibrator mechanism for interrupting the primary circuit of said induction coil comprising a magnet winding, a stationary core member, a movable core member, an interrupter contact moved by said movable core member, said movable core member and said contact constituting a movable system having small inertia, and a closed

circuit of high conductivity associated with said winding.

15. Ignition apparatus comprising the combination with a source of current, of an induction coil, and vibrator mechanism for interrupting the primary circuit of said induction coil comprising a magnet winding external to said induction coil, a stationary core member therefor terminating within said winding, a movable core member terminating adjacent said stationary core member within said winding, and an interrupter contact moved by said movable core structure.

In testimony whereof I have hereunto affixed my signature this 16th day of June, 1919.

FRANK AIKEN.
